J. H. PHILLIPS.

WATER HEATER.

(Application filed Sept. 25, 1899.)

(No Model.)

Attest *E. M. Wiggins*
A. J. Thairing Inventor
Joseph Howard Phillips
by C. Spengel Atty.

UNITED STATES PATENT OFFICE.

JOSEPH HOWARD PHILLIPS, OF CINCINNATI, OHIO.

WATER-HEATER.

SPECIFICATION forming part of Letters Patent No. 650,866, dated June 5, 1900.

Application filed September 26, 1899. Serial No. 731,601. (No model.)

To all whom it may concern:

Be it known that I, JOSEPH HOWARD PHILLIPS, a citizen of the United States, and a resident of Cincinnati, Hamilton county, State of Ohio, have invented certain new and useful improvements in Water-Heaters; and I do declare that the following is a clear, full, and exact description of the invention, such as to enable others skilled in the art to which it applies to make and use the same, attention being called to the accompanying drawings, with the reference-numerals marked thereon, which form also a part of this specification.

This invention relates to appliances for heating quickly and conveniently water for any purpose, but more particularly for household uses. Such heaters are usually connected with a hot-water reservoir, generally in form of a customary kitchen-boiler, in which the water heated is stored for ready use. This boiler, as well as the heater which supplies it, forms part of the pipe system which is usually connected with a waterworks-service. The arrangement is such that the cold water is received by the heater, by which it is heated, and then delivered to the boiler, from which in due time hot water under pressure may be drawn. During such times and intervals when no hot water is drawn the same accumulates and increases the supply in the storage-boiler, such accumulation being due to a movement of the water induced by the difference of its temperature within different parts of the heater. The effect of this movement is such that hot water continually passes from the heater to the boiler, to be followed by cold water either from the pipe system or from the boiler, being in the latter case such water as is displaced by the hot water. The heat is obtained from any suitable fuel, gas (either manufactured or vaporized) being generally preferred.

My improved heater consists, substantially, of a series of pipes, and one of the features of my invention relates to their arrangement, which is such as to obtain the aforesaid movement of the water for the purpose of delivering constantly hot water to the boiler and storing it therein. An important feature of this arrangement is the utilization of the expended heat to the fullest possible limit not only in its direct action, but also by using

previously-heated water to aid in heating subsequently-entering cold water.

Another feature of my invention is an arrangement and construction which lessens the deleterious effects of contraction and expansion upon the metal due to rapidly-changing temperatures—as, for instance, when larger quantities of hot water are drawn at once and the place of which in the heater is suddenly taken by cold water.

An additional feature of my invention is the ability to completely drain and flush the heater to free it from sediment.

There are also certain features pertaining to details of construction, which will be fully referred to in proper order.

In the following specification, and particularly pointed out in the claims at the end thereof, is found a full description of my invention, together with its operation, parts, and construction, which latter is also illustrated in the accompanying drawings, in which—

Figures 1 and 2 are vertical sections taken at planes about at right angles to each other. Figs. 3 and 4 are horizontal sections taken, respectively, on lines 3 3 and 4 4 of Fig. 2. Fig. 5 is a top view of the detached head or manifold at the lower end of the heater, portions being broken away.

This invention consists, substantially, of a series of heating-pipes, a source of supply to them in shape of a cold-water pipe, a delivery-pipe common to them all which carries off the water heated by them, and means whereby the heating-pipes and this delivery-pipe are connected in a manner to enable this latter to draw the water from all the heating-pipes, the operation being such as to obtain the desired motion of the water, which causes the hottest water to constantly leave the heater, making room for colder water to be also heated. The heating-pipes consist of two sets of pipes, one in which the water ascends and which delivers it to the second set, in which the water descends. 8 indicates the pipes of the ascending set, having their lower ends all communicating with an annular chamber 9, which receives the cold water from the service-pipe 11. Their upper ends are open and communicate with the descending pipes 12, which are of larger dia-

ter and inclose and overtop pipes 8. Their upper ends are closed, while their lower ends are open and communicate with another annular chamber 13. These two chambers 9 5 and 13 are preferably contained in one casting or head, forming a manifold for all the pipes, the two chambers being separated from each other by a diaphragm 14, into which the lower open ends of pipes 8 are tapped. The 10 lower open ends of pipes 12 are tapped into the top of this head. Chamber 9 supplies the water to the ascending pipes 8, which deliver it at their upper ends to the descending pipes 12, which convey it to chamber 13, from 15 which it is taken by a central discharge-pipe 15, which delivers the heated water to the boiler. (Not shown.)

The burner 16, of any approved style, preferably an atmospheric ring-burner, is attached 20 to the lower part of the heater in a manner to be concentric with the head, the method of attachment being preferably by a screw connection to the latter. For such purpose each has a vertical flange, one, 17, projecting from the 25 head downwardly, the other, 18, from the burner upwardly, and each being correspondingly threaded to be capable of entering into engagement with the other. As to one of the 30 engaging parts this flange may simply consist of threaded lugs. The gas or mixture of gas and air is supplied to this burner by a pipe 19.

While pipes 8 and 12 are described as 35 "heating-pipes," it will be noted that the heating of the water is not restricted merely to them, but proceeds also while the water is contained in the manifold or head and continues during its entire passage through pipe 15, since all these parts are subject to and 40 exposed to the action of the flames of the burner and the air heated thereby. The whole collection of pipes is surrounded by a jacket 21, having an opening 22 at its upper end, which insures the necessary draft, and may be 45 connected with a flue to carry off any products of combustion. The water contained and arriving in pipe 15 having been the longest time in the heater is necessarily the hottest, and therefore also the lightest, and for which 50 reason it constantly rises in this pipe. This motion causes the cooler water to pass out of chamber 13 and down in pipes 12, to be followed by cold water, which rises in pipes 8. The coldest water is received at the hottest 55 place of the heater, which is the lower chamber 9 of the flame-surrounded head and where the heating starts at once, continuing while the water ascends in pipes 8, the heat here being received from the hot water surrounding 60 them and descending in pipes 12, and which latter are in direct contact with the heat from the burner. Chamber 13 collects this water from all pipes 12, after which it is taken by pipe 15, in which the heating is

continued and also finished. The injurious 65 effects upon the metal by its contraction and expansion being a prolific source of cracks and leaky joints and due to rapid changes of temperatures when hot water is drawn, which causes at once cold water to enter the heater, 70 are very much reduced by the fact that only a limited part of the heater receives such cold water, and which part is chamber 9. The same being cast metal, the deleterious effects are still more counteracted. In the further 75 progress of the cold water through pipes 8 this contrast is not so marked, since these latter are not exposed to direct heat. This tendency to reduce contrast between temperatures also prevents condensation on the 80 outside of the pipes and avoids objectionable accumulation of drippings below the heater. 23 is a blow-off cock by means of which when open the heater may at any time be completely drained and flushed for the purpose 85 of freeing it from sediment.

Having described my invention, I claim as new—

1. In a water-heater, the combination of a series of upright heating-pipes, a jacket 90 which surrounds them, an annular head or manifold to which all their lower ends connect, a supply-pipe delivering cold water to the lower part of the heater, a discharge-pipe receiving the water collected in the manifold and delivering hot water at the upper end of the heater, a burner below the lower end of the latter and screw-threaded projections on the upper part of the burner and on the lower part of the head, which projections 100 are adapted to engage each other for the purpose of holding the burner in place.

2. In a water-heater, the combination of a cast-metal head having annular chambers 9 and 13, one above the other, a diaphragm dividing them, upright heating-pipes connected to each chamber and also communicating with each other, thereby establishing also communication between these chambers, a supply-pipe delivering cold water to the lower 110 chamber which latter distributes it to the heating-pipes, a central discharge-pipe connected at its lower end to upper chamber 13 taking therefrom the water collected therein and delivering it now heated at the top of the 115 heater, a jacket open at its upper end surrounding all the pipes and means at the lower part of the heater to apply heat against the chambered head, the circulation of which heat is upwardly and surrounds the heating- 120 pipes and the discharge-pipe.

In testimony whereof I hereunto set my hand in presence of two witnesses.

JOSEPH HOWARD PHILLIPS.
